OTTO WEINSTEIN, OF BOSTON, MASSACHUSETTS, ASSIGNOR TO STANDARD NECK-WEAR COMPANY, OF BOSTON, MASSACHUSETTS, A CORPORATION OF MASSACHUSETTS.

METHOD OF MAKING NECKTIES.

Application filed October 23, 1926. Serial No. 143,633.

This invention relates to neckties and more particularly to ties of the four-in-hand type.

The principal object of the invention is to provide an improved method of cutting out 5 the patterns or blanks from which such ties are made, from a piece of fabric in a manner to secure the minimum waste of material. Other objects are to devise an improved method of folding and finishing the blanks in order 10 to produce a completed tie of attractive appearance.

In order that the invention may be readily understood, reference is had to the accompanying drawing, forming part of this specification, and in which:—

Figure 1 is a fragmentary view of a piece of fabric showing my improved method of laying out necktie patterns thereon;

Figure 2 is a view of one of the patterns 20 or blanks after it has been cut from the fabric, parts being broken away;

Figure 3 is a view of the wrong or reverse side of a completed tie, showing the method of finishing; and

Figure 4 is a perspective view on an enlarged scale showing some of the details of construction.

Referring to the drawing in detail, 1 designates a piece of suitable fabric such as silk 30 or the like, which is of indefinite length and of such width as to contain an even number of patterns. In the drawing, only the left hand portion of the width of the piece is shown, the remainder being broken away.

The patterns are laid out on a section of fabric of sufficient length to properly accommodate them, such, for example, as the section comprised between the lines x and y in Figure 1. I make my improved pattern in two 40 parts, a wide end portion and a narrow end portion. A complete set of patterns comprises a pair of each of these parts, all of which parts are laid out side by side longitudinally of the piece of fabric.

The pattern for the wide end portion of the tie is indicated at 2 and it will be seen that 45 a pair of such patterns are laid out side by side in reverse arrangement, with the small ends extending in opposite directions. One 50 side edge of each pattern 2 such as indicated at 2^a , is perfectly straight and parallel with

the edge of the piece of fabric, or in other words, is parallel with the warp of the fabric. In fact, the edge 2^a of the left hand pattern 55 2 coincides exactly with the edge 1^a of the piece of fabric.

Each wide end portion comprises a part which is to constitute the tying area and a part 3, adjacent the small end, which constitutes part of the neck band of the finished tie. 60

The other wide edge of each pattern extends at an angle to the edge of the piece of fabric, and the adjacent edges of the two patterns meet on a common diagonally extending line 2^b .

In order to save material, and to get as many patterns as possible within the width of the piece, it will now be particularly noted that the end of each pattern, at its point of maximum width, overlaps to some extent the 70 neck band portion of the adjacent pattern. In other words, the corner of each pattern projects into the neck band of the other, as indicated at 4. By virtue of this arrangement, the patterns can be crowded much more 75 closely together, transversely of the piece of material, than they otherwise could. Moreover, the only waste in the material is found in the small triangular sections 1^b at each side of the pointed end 2^b of each pattern, and this 80 waste is almost negligible.

To be used in connection with the pair of patterns for the wide end portion, I provide a pair of patterns for the small end portion of the tie, and these are indicated at 5. From 85 an inspection of Figure 1, it will be seen that these patterns are of uniform width throughout, and are arranged side by side in parallel relation. The left hand one of these patterns also joins the edge 2^a of the right hand large 90 end portion pattern 2. In other words, the adjacent patterns 2 and 5 meet on a common line 2^a , which extends longitudinally of the fabric. One end of each of the patterns 5 is cut off square, as indicated at 5^b , while the 95 opposite end is preferably pointed, as shown at 5^a . The squared off end 5^b is adapted to be united to the similarly squared off end 3^a of the neck band part 3 of the wide end portion pattern, the part 3 being of the same width 100 as the pattern 5.

The patterns having been laid off, as de-

scribed, are then cut out from the fabric, the cutting being done in such a way as to preserve intact the full width of the free end of the free wide end of each pattern 2 while 5 correspondingly mutilating the adjacent neck band portion of the other pattern.

Each of the complete patterns, comprising assembled wide and narrow end portions, will therefore have the appearance shown in Figure 2. From an inspection of this figure, it 10 will be seen that the part 3 of the neck band portion which forms a part of the pattern 2 has been cut away to form a notch 4, the width of the blank or pattern at this point being 15 considerably less than the other points of the neck band. It will also be seen that the square end portions 3^a and 5^b of the parts 3 and 5, respectively, have been united by stitching, the arrangement being such that the lower 20 edge of the assembled blank forms a single straight line, as indicated at 2^a.

The blank thus formed is then folded longitudinally and the edges brought over and stitched together. The wide end portion of 25 the tie has a central longitudinal seam 9 extending substantially throughout the length thereof, where the folded over edges meet, as shown in Figure 3. The neck band portion of the narrow end section 5 similarly has its 30 edges folded over and stitched together as indicated at 6. In order to produce a flaring small end, however, the edges of the free end portion of the section 5 are not brought close together, but are turned over and stitched to 35 a tapering piece of fabric 10, as indicated at 6^a. In other words, in order to save material, I cut the narrow end portions 5 of uniform width throughout. Then, in order to produce the desired flare to the end portion of the tie, 40 I employ an additional piece of material 10 of tapering form and interpose it between the overturned edges of the main material so as to increase the width of the tie toward the end thereof.

Referring now to Figure 4, the nature and 45 position of the mutilation or notch 4 will be better understood, and it will be seen that this notch occurs on the reverse side of the neck band portion of the tie near the middle. In order to hold the material in shape at this 50 point, a short line of stitching 7 is preferably employed between the notch and the edge of the tie.

In finishing my improved tie, I employ the 55 usual strip of anti-friction fabric such as satin, at the neck band portion, to cause the tie to slip more readily through the collar. This strip is indicated at 8 in Figures 3 and 4, and it will be seen that the notch or mutilation 60 4 is so located as to be covered and entirely concealed by this strip 8 when the same is sewed down into position. Thus, the appearance of the finished tie to the purchaser 65 will be the same as though the defect or mutilation 4 were not present, and since this de-

fect is entirely covered by the anti-friction band or strip, it in no way detracts from the attractiveness or serviceability of the tie.

What I claim is:—

1. The method of producing a four-in-hand tie from a regular piece of fabric which comprises laying out a pair of patterns for the wide end portions of said ties longitudinally on said fabric, side by side, in reverse arrangement, the longitudinal side edges of 70 said patterns remote from each other extending parallel with the edge of said piece, and the adjacent side edges of said patterns meeting on a common line extending at an angle to the edge of said piece.

2. The method of producing a four-in-hand tie from a regular piece of fabric which comprises laying out a pair of patterns for the wide end portions of said ties longitudinally on said fabric, side by side, in reverse 75 arrangement, with one of their side edges parallel with the edge of said piece and a separate pair of patterns for the narrow end portions of said ties also longitudinally on said fabric, side by side, in parallel relation, and adjacent the parallel edge of one of the patterns for the wide end portion, the patterns for the narrow end portions being of uniform width throughout their length, and each having 80 one square end.

3. The method of producing a four-in-hand tie from a piece of fabric which comprises laying out a pair of patterns for the wide end portions of said ties longitudinally on said fabric, side by side, in reverse arrangement, each pattern having at one end, part of a neck band portion, the other end of each pattern, at the point of maximum width, overlapping the said neck band portion of the adjacent pattern, and cutting out said patterns from the fabric so as to preserve intact the wide end of both resulting blanks, while mutilating the neck band portion thereof.

4. The method of producing a four-in-hand tie from a piece of fabric which comprises laying out a pair of patterns for the wide end portions of said ties longitudinally on said fabric, side by side, in reverse arrangement, each pattern having at one end, part of a neck band portion, the other end of each pattern, at the point of maximum width, overlapping the said neck band portion of the adjacent pattern, cutting out said patterns from the fabric so as to preserve intact the wide end of both resulting blanks, while mutilating the neck band portion thereof, 110 uniting each such blank with a suitable narrow end portion blank, and folding and stitching to form a tie, and finally applying 115 a strip of fabric over the mutilated portion of the neck band to conceal the same.

5. The method of producing, as a separate article, the narrow end portion of a four-in-hand tie from a piece of fabric which com- 120

prises laying out the patterns therefor longitudinally on said fabric, side by side, each pattern being of uniform width throughout, cutting said patterns from the fabric to form 5 blanks, folding over the side edges of each blank, bringing together and uniting such folded edges at one end portion only of the

blank to form a neck band, such edges being spaced apart at the other end portion only of the blank, and interposing between and 10 stitching to said spaced edges a tapered strip of fabric, so as to form a flaring free end.

In testimony whereof I affix my signature.

OTTO WEINSTEIN.
